UNITED STATES PATENT OFFICE.

GERHARD A. DRERUP AND HOWARD CRAMER, OF GARRETT, INDIANA.

FARM-GATE.

1,237,881.

Specification of Letters Patent. Patented Aug. 21, 1917.

Application filed April 19, 1916. Serial No. 92,150.

To all whom it may concern:

Be it known that we, GERHARD A. DRERUP and HOWARD CRAMER, citizens of the United States of America, and residents of Garrett, 5 in the county of Dekalb and State of Indiana, have invented certain new and useful Improvements in Farm-Gates, of which the following is a specification.

This invention relates to improvements in 10 farm gates of that class in which means are provided for sustaining the gate in swinging position at various heights as may be required to clear accumulations of snow and other obstructions, or to admit egress and 15 ingress of smaller stock while detaining the larger stock. The object of the improvement is to so construct the sustaining mechanism as to permit the gate to be lifted to the desired elevation and to support the 20 same in its elevated position, and further to effect the release of the sustaining mechanism readily so that the gate may be quickly lowered.

The object of the invention is accomplished by the construction illustrated in the 25 accompanying drawings in which:—

Figure 1 is a side elevation of a gate in 30 swinging position with the invention applied thereto, the gate being shown broken away;

Fig. 2 is a vertical section of Fig. 1 on the line $x-x$;

Fig. 3 is a plan view of Fig. 1 with the 35 gate shown in transverse section on the line $y-y$ of Figs. 1 and 2; and

Fig. 4 is a detail view in perspective of the tumbling member.

Similar characters of reference indicate 40 corresponding parts throughout the several views and referring now to the same:

1 is a fence-post having horizontally extending eyebolts (2) in which is mounted a vertical shaft (3). 4 is a gate made up of horizontal boards (5) and (6) that are secured 45 between vertical slats (7) and (7'). At the inner end of the gate the boards (5) extend beyond the slats (7') and have connected at their respective ends a timber (8) that extends parallel with said slats at a 50 suitable distance therefrom leaving a runway (9) therebetween. An arm (10) is loosely mounted upon the shaft (3) and extends horizontally through a vertical slot (11) made in the timber (8). A pin (12) 55 extends through the forward end of the arm (10) and has loosely mounted upon its ex-

tending ends corresponding rollers (13) against which the inner face of the timber (8) bears, and thus the upper portion of the timber is held in hinged and vertically movable relation with the shaft (3). A bracket (14) is secured to the lower portion of the timber and extends rearwardly therefrom, and the shaft (3) extends therethrough. A roller (15) is mounted in the bracket and bears against the adjacent face of the shaft (3). Thus the lower portion of the timber has also hinged and vertically movable relation with the shaft. The bracket (14) bears downwardly upon the lowermost eye-bolt (2) and supports the gate in its lowermost position. In the lower forward face of the timber (8) is fixed a notched member (16), the lower end of which has a forwardly curved guide (17) that extends across the runway (9). A tumbling member (18) is pivotally supported within the runway at the ends of the loosely hanging arms (19), the latter being linked at their upper ends in corresponding ears (20) that project oppositely from a plate (21) that is mounted upon the shaft (3) above the arm (10). The tumbling member (18) has oppositely extending wings (22) and (23) respectively that have also opposite curvature, and has 85 also a jaw (24) through which an opening (25) is made for the pin (26) upon which it is loosely mounted and which is connected in the respective ends of the arms (19).

In the operation of the device the gate 90 hangs normally in its lowermost position with the bracket (14) bearing upon the lowermost eye-bolt and the upper portion of the timber (8) bearing against the rollers (13) so that the gate thus supported may 95 swing to and fro upon the shaft (3). When it is desired to elevate the gate, it is lifted so that the notched member engages the jaw (24) on the tumbling member so that the jaw becomes engaged in one or the other 100 of the notches, (27) (28), or (29). The gate will then be supported in its corresponding elevated position by the tumbling member which is carried by the arms (19). When it is desired to lower the gate, the tumbling 105 member may be disengaged by raising the gate so that the wing (23) will come into contact with the guide (17) whereupon the wing (22) will automatically gravitate into the notch (29). When the gate is then lowered the tumbling member will revolve and during the downward passage of the gate 110

the wing (23) will enter the notch (27) so that as the gate continues its downward movement the member becomes further revolved, in the operation making one complete revolution. In making the revolution the jaw of the tumbling member is turned away from the notches so as not to engage therewith. It will therefore appear that when the gate is raised to its uppermost 10 limit the tumbling member will become ineffective as a support for the gate during the lowering movement thereof.

What we claim is:—

1. In a gate of the class described, a gate proper; a vertical timber in connection with the gate at the inner end thereof, the gate and timber being spaced apart to leave a run-way therebetween; a post having two eye-bolts extending therefrom; a shaft extending through the eye-bolts; a bracket secured to the timber and having a roller mounted therein adapted to bear against the shaft; an arm in connection with the shaft extending loosely through the timber, the latter having a vertical slot made therein for the same; rollers mounted in connection with the arm extending within the run-way and bearing against the forward face of the timber; a notched member secured to the forward face of the timber near the lower end thereof and having a forwardly curved guide at its lower end; a plate in connection with the shaft; a pair of pendant arms linked to the plate; and a tumbling member pivoted between the arms and extending

in the run-way and adapted to engage the notched member when the gate is elevated.

2. In a gate of the class described, a gate proper having a vertically disposed timber at its rear end, the gate and timber being spaced apart to leave a run-way therebetween; a shaft mounted in vertical position for supporting the gate; an arm in connection with the upper part of the shaft and extending loosely through the timber, there being a vertical slot made therein for the same; rollers mounted upon the arm within the run-way and bearing against the forward face of the timber; a notched member secured to the timber at the lower portion of the run-way and having a forwardly curved guide at its lower end; a pair of pendant arms having supported relation with the upper end of the shaft; and a tumbling member pivoted between the lower ends of the arms and being adapted to engage the notches in said notched member and support the gate in elevated position accordingly, and being adapted also to become shifted from engagement with the notched member by said guide when the gate is elevated to its extreme height.

In testimony whereof we affix our signatures, in presence of two witnesses.

GERHARD A. DRERUP.
his
HOWARD X CRAMER.
